UNITED STATES PATENT OFFICE.

THOMAS B. ATTERBURY, OF PITTSBURG, PENNSYLVANIA.

DESIGN FOR A DISH-COVER.

SPECIFICATION forming part of Design No. 19,247, dated August 6, 1889.

Application filed July 2, 1889. Serial No. 316,338. Term of patent 7 years.

To all whom it may concern:

Be it known that I, THOMAS B. ATTERBURY, a citizen of the United States, residing at Pittsburgh, in the county of Allegheny and State of Pennsylvania, have invented and produced a new and original Design for Dish-Covers; and I do hereby declare the following to be a full, clear, and exact description of the same, reference being had to the accompanying drawings, forming a part thereof.

In the drawings I have shown a dish-cover in general form that of a mound.

The main feature of my design consists in the configuration of two or more fishes symmetrically arranged around a central portion, which extends above the fishes a little distance in the form of a truncated cone, having a shell on top thereof, which forms the handle of the dish-cover.

20 In the illustration of my design in the accompanying drawings two complete fishes are shown formed in relief, with eyes, fins, and scales, all shown in exact representation of the form of the fish. The fishes are formed around the central portion of the cover with fins raised, so as to form a conventional design when looked down upon.

Referring to the drawings, Figure 1 is a perspective of the cover. Fig. 2 is a top or plan view of the same.

30 A indicates the fishes which surround the central portion B, having the shell C thereon. Below the fishes the cover is made in representation of water or the crest of a wave, indicated by the letter D, which gives the fishes 35 the appearance of having been left on the beach or tossed out of water by a wave.

What I claim is—

A design for a dish-cover, consisting of the representation of two fishes formed in relief 40 around the central portion of the cover, as herein described and shown, said central portion extending upward in the form of a truncated cone and having a shell formed on the top, while below the fishes the cover is made 45 in representation of water.

In testimony whereof I affix my signature in presence of two witnesses.

THOMAS B. ATTERBURY.
